UNITED STATES PATENT OFFICE.

JOHANNES FLEISCHER, OF COLOGNE, GERMANY.

STEAM COOKING APPARATUS.

SPECIFICATION forming part of Letters Patent No. 242,526, dated June 7, 1881.

Application filed March 3, 1881. (No model.) Patented in Germany April 4, 1880.

To all whom it may concern:

Be it known that I, JOHANNES FLEISCHER, a citizen of Germany, residing at Cologne, in the Empire of Germany, have invented certain new and useful Improvements in Steam Cooking Apparatus; and I do hereby declare the following to be a full, clear, and exact description of the invention, such as will enable others skilled in the art to which it appertains to make and use the same, reference being had to the accompanying drawings, and to the letters or figures of reference marked thereon, which form a part of this specification.

The present invention relates to that class of steam cooking apparatuses in which a series of cylindrical vessels or pots are fitted one within the other, or are superposed so as to form a vertical nest of pots or vessels.

The invention consists in the construction and combination of parts, which will be hereinafter more fully described, and then set forth in the claims.

In the drawings, Figure 1 is a vertical sectional view of a cooking apparatus constructed according to the present invention. Fig. 2 is a transverse section taken through the heating chamber or base containing the means for generating steam. Figs. 3 and 4 are transverse sections taken upon different horizontal planes passing through the apparatus.

The apparatus is heated by means of a gas or petroleum burner or coal-stove. In the present instance a cylindrical base, A, serves for the reception of the gas-stove B. The lower portion, C, of the cylinder or base A serves as a water-reservoir, which is traversed by a vertical air-supply pipe, D. a is a drain-cock for drawing off the hot water. b' b'' b''' are legs upon which the cylinder or base rests. c are slots for permitting the escape of the products of combustion.

Upon a flange, d, or projecting lugs located near the top of the base A, rests a cylindrical boiler, E, the bottom F of which, in order to increase the heating-surface thereof, is provided with a dome-shaped extension, G. The steam generator or boiler E is filled with water and the soup-pot H is inserted therein. The boiler E and a cylindrical bottom-extension, I, of the soup-pot serve to form an airtight joint, similar to a hydraulic packing, between the vessels H and E. One end of a

steam-pipe, e, is secured to the soup-pot, the other end of said pipe being provided with a brass collar, x, which fits into a depending ring 55 or socket, z, on the pot K, so as to insure a steam-tight joint at the point where the pipe e enters the steam-space of the pot K.

A roasting or baking vessel or pot, K, is fitted upon the pot H. It has two bottoms, g 60 and f, and the space p between the same is connected by the aforesaid pipe e with the pot H. The lower bottom, f, of the baking or roasting vessel K is inclined toward the pipe e, so as to carry off the water of condensation. 65 c' is a vertical pipe connected with the bottom, g, and ending in an upper collar or plug, y. The vessels K and H are adjusted or registered upon each other by means of a flange, d', and in order to secure a tight fit between 70 z and x the vessel K rests upon x, and also upon two points, v and w, formed of small globes, which, together with x, constitute the corners of an equilateral triangle.

L is another vessel, which serves for the reception of vegetables and potatoes placed in the insertible vessels M and N fitted into the same. This vessel L is guided into position by means of a flange, d'', similar to d', and rests upon the collar or plug y by an upwardly-projecting ring, o, on its bottom, and is also supported upon the points v' and w', of similar construction to v and w, above described.

m is a lid of the upper kettle, L, and n are handles of the several vessels. 85

There may be two or more roasting or baking vessels, K, arranged above each other and connected together.

In order to increase the heating-surface the soup and the baking or roasting vessels may 90 be provided with double cylindrical side walls, closed on top, and so connected to the double bottom as to form a continuous space around the sides and bottom of the pot.

The operation of my apparatus is as follows: 95 The bottom support or base, A, and the boiler E are filled with water, after which the soup-pot H is inserted into the boiler E and supplied with the meat, vegetables, and water as soup ingredients. The boiler is then covered with 100 the baking or roasting vessel K, which receives the meat to be roasted, and is itself covered with the vegetable-pot L. The latter contains the vegetables and potatoes, which are placed

in the insertible vessels M and N, or into a single vessel or receptacle. The heating apparatus B is now fired or ignited, which causes the water in the vessel E to boil. The heat 5 which radiates in a downward direction from the heating apparatus is received and absorbed by the water C, and thus warm water is produced, which can be drawn off for use at pleasure by means of a drain-cock, a. As soon as 10 steam is formed the soup-pot H is heated with indirect steam from above and below by means of the pipe e. The same result takes place with the roasting-vessel H, and thus the contents of the same are roasted, and at the same 15 time the wet steam is completely shut off from the same. Thence the steam enters the upper pot, L, by means of the pipe e', where it condenses and returns to the water-kettle. The water of condensation is collected on the bottom 20 of the pot L and cannot run off except through the opening in the same.

Instead of the gas or petroleum heating devices a coal fire or stove may be employed, in which case the support A is dispensed with.

25 The cooking vessels or pots, instead of being made cylindrical in shape, may be of any other preferred form, and two or more of such vessels may be placed one upon another.

My apparatus may also be used for boiling 30 tea, coffee, milk, and eggs, for which purpose specially-constructed pots are employed. For making coffee or tea the pots are so constructed that the boiling water is caused to pass through the substances by means of steam-pressure. 35 For the purpose of boiling eggs a pot having a sieve or perforated bottom is employed, the eggs being placed upon the same.

Having thus described my invention, what I claim as new is—

40 1. In a cooking apparatus, the combination

of a base or support, A, serving as a hot-water reservoir, and having a vertical air-supply tube, D, and openings in its walls for the escape of the products of combustion, with a heating apparatus arranged between said openings and the 45 air-supply tube, and a superposed boiler or cooking-vessel, as and for the purpose set forth.

2. In a cooking apparatus, the combination of the cooking-vessel H, having a shell, I, depending from its bottom, with the steam-generating vessel E, inclosing said shell I and made of the same length as the latter, as and for the purpose set forth.

3. In a cooking apparatus, the combination of a cooking-vessel having a vertical steam-tube provided with a collar or packing-plug at its upper end, with a superposed cooking-vessel having a double bottom or steam-chamber and a ring or socket for receiving the collar of the steam-tube, as and for the purpose set forth. 55

4. The combination of the top steaming chamber or vessel, L, having an apertured bottom, the cooking-vessel K, arranged below the latter, having a steam-tube entering said apertured bottom and communicating with a steam-space or double bottom of the cooking-vessel K, with a steam-generating vessel and heating apparatus, as and for the purpose set forth. 65

5. In a cooking apparatus, a food receptacle or pot having a double bottom, the lower plate 70 forming said bottom being inclined or made slanting and provided with a steam-inlet tube, as herein set forth.

In testimony whereof I affix my signature in presence of two witnesses.

JOHANNES FLEISCHER.
